DESIGN FOR AN EARRING CLASP

Gretyl E. Carson, New York, N. Y.

Application September 23, 1944, Serial No. 115,432

Term of patent 14 years

(Cl. D45—9)

To all whom it may concern:

Be it known that I, Gretyl E. Carson, a citizen of the United States, residing at the city of New York, in the county of New York and State of New York, have invented a new, original, and ornamental Design for an Earring Clasp, of which the following is a specification, reference being had to the accompanying drawing, forming part thereof.

In the drawing:

Figure 1 is a front elevational view of an earring clasp showing my new design.

Figure 2 is a side elevational view thereof, and Figure 3 is a top plan view of the earring clasp as shown in Figure 2.

I claim:

The ornamental design for an earring clasp, as shown.

GRETYL E. CARSON.
